UNITED STATES PATENT OFFICE.

DAVID P. CLARK, OF DAYTON, OHIO.

TOY.

1,087,277.

Specification of Letters Patent.

Patented Feb. 17, 1914.

Application filed July 14, 1913. Serial No. 778,869.

To all whom it may concern:

Be it known that I, DAVID P. CLARK, a citizen of the United States, residing at Dayton, in the county of Montgomery and 5 State of Ohio, have invented certain new and useful Improvements in Toys, of which the following is a specification, reference being had therein to the accompanying drawing.

10 This invention relates to toys and more particularly to wheeled toys of the self propelled type.

The object of the invention is to provide a toy of this character capable of movement in either direction, the movement of which will be automatically reversed by the jar caused by the toy coming in contact with an obstruction.

A further object is to provide such a toy 20 having frictional driving devices and in which the weight of the motor mechanism and the motor frame will rest upon the driving mechanism and increase the effectiveness of the frictional contact; 25 further, to provide a device in which the motor carriage will be bodily movable from one position to another to drive the toy in different directions; further, to so arrange the driving mechanism that when the motor 30 frame is in either position the driving action of the driving mechanism will tend to hold the frame in that position and to maintain the frictional driving connections in their most effective positions.

35 In the accompanying drawings, Figure 1 is a longitudinal, sectional view taken on the line A A of Fig. 3, showing the motor frame and mechanism in elevation; Fig. 2 is a sectional view taken on the line B B of Fig. 1 showing the motor frame and driving mechanism in plan; Fig. 3 is a transverse, sectional view, taken on the line C C of Fig. 1 and looking in the direction of the arrows; and Fig. 4 is an end elevation.

45 In these drawings I have illustrated one embodiment of my invention and have shown the same as embodied in a toy built to represent an electric locomotive, but it will be understood that the shape of the 50 body of the toy is not a part of the invention and may be varied at will. In this particular form of the toy the body or housing which incloses the mechanism, as indicated at 1, is entirely separate from and is 55 removably mounted on a main frame in which are journaled the wheels and which

carries the removable motor frame and driving mechanism. As here shown the main frame comprises parallel side members 2 connected at their ends by means of transverse end members 3 having flanges 4 to which the removable body or housing is secured by means of bolts 5. The main frame is supported by wheels 6 which are here shown as track wheels and both pairs of 60 which constitute, at different times, the driving wheels. Each pair of these wheels is rigidly secured to an axle 7 which is journaled in the main frame. Preferably, each axle is mounted in a vertical slot 8, the 65 length of which is sufficient to permit the frame to have a slight movement relatively to the axle.

In the present type of toy the power is derived from an inertia wheel 9 which is 70 rigidly secured to a shaft 10 journaled at one end in one of the side members of a motor-supporting frame 11 and at the other end in an intermediate frame member 12 rigidly secured to and forming a part of 75 said motor-supporting frame. The inertia wheel shaft 10 has secured thereto pinions 13 which mesh with gears 14, which, in turn, mesh with gears 15. Both the gears 14 and 80 15 are rigidly connected with driving pinions 16 and 17, respectively, which are adapted to engage the peripheries of the 85 respective driving wheels. These pinions are here shown as friction pinions having tapered grooves, but any suitable type of 90 pinion may be employed. It will be noted that the connection between the inertia wheel shaft and the driving pinion 16 is a direct connection, that is, the pinion 13 meshes directly with the gear 14 of the driving pinion 16, while the connection of the inertia wheel shaft with the driving pinion 17 is through an intermediate gear, the gear 14 of the pinion 16 acting as such intermediate gear. Consequently, the rotation of the 95 inertia wheel shaft in one direction will serve to rotate the driving wheels in opposite directions. I have herein shown the arrangement of the pinions the same on both sides of the toy, that is, there is a 100 pinion 16 on each side of the toy and a pinion 17 on each side of the toy. In this manner I secure a driving action on both driving wheels of each pair, but it will be understood that this is not essential to an 105 embodiment of the invention.

As stated, the driving pinions 16 and 17

are adapted to operatively engage the driving wheels of the respective ends of the main frame. To this end the motor supporting frame is mounted so that it is capable 5 of bodily movement, which movement will serve to carry the driving pinions toward or away from their respective wheels 6. As shown in the drawings the motor supporting frame occupies an intermediate position and 10 none of the driving members is in operative engagement with its wheel. In this particular embodiment of the toy I have shown the motor-supporting frame as having a sliding movement upon the main frame and to this 15 end the two side members of the main frame are provided with longitudinal slots 18 to receive guides or studs 19 projecting from the sides of the motor supporting frame. The studs are so arranged that they will engage 20 the ends of the slots when the driving pinions have assumed their proper relative positions with relation to their respective driving wheels, and in this connection it will be noted that the direction of rotation of the 25 driving pinions is always opposite the direction in which the toy is moving, and inasmuch as these pinions operate upon the rear wheels the direction of rotation of the pinions is such that they tend to move the motor-supporting frame rearwardly and thus 30 maintain themselves in the proper relation to their wheels.

In order to secure the proper driving contact between the friction pinions and the 35 wheels it is desirable that they should be so arranged that when in operative engagement with their respective wheels they will support a very considerable portion of the weight of the motor-supporting frame and 40 driving mechanism and, if desired, a portion of the weight of the main frame. By making the grooves 18 of a width slightly greater than the diameter of the studs 19 and mounting the pinions so that their lower 45 edges will extend slightly below the upper edges of the wheels these pinions, when moved toward their respective driving wheels, will engage the upper edges of those wheels and lift the studs of the motor-supporting frame off the lower edge of the slots, 50 thus transferring the weight from the studs to the pinions. However, in the present form of the toy I utilize not only the weight of the motor-supporting frame and the 55 parts carried thereby, but also a portion of the weight of the main frame. I have, therefore, allowed for no material movement of the studs vertically in the slots but have mounted the axles in slots in the main frame. 60 Consequently, when the motor-supporting frame is moved toward one end of the main frame the pinions will engage the upper portions of the wheels and as they ride over the same will move the studs of the motor-supporting frame into contact with the up-

per edges of the slots in the main frame and will lift that end of the main frame, thus transferring the weight thereof, as well as the weight of a large portion of the motor-supporting frame, to the pinions. The motor-supporting frame slides very freely upon the main frame and if the toy, when moving in one direction, comes in contact with an obstruction the jar will be sufficient to impart a sliding movement to the motor-supporting frame and thus move the driving pinions out of engagement with the rear wheels and cause the other pair of driving pinions to come in engagement with the front wheels, thereby reversing the movement of the toy and causing that pair of driving wheels which had been the front wheels to become the rear wheels. In the practical embodiment of the toy it can be reversed in this manner several times and 85 without reversing will travel for long distances.

The power may be generated in the inertia wheel in the manner common to inertia wheel toys, that is, by moving the driving pinions into contact with one pair of driving wheels, pressing down on the frame of the toy and moving the same over the floor, thus rotating the inertia wheel. When sufficient speed has been attained the toy may be 95 released and the inertia wheel will then impart a forward movement to the toy. To retain the driving pinions in proper engagement with their driving wheels during this starting movement of the toy I have mounted 100 on the top of the motor-supporting frame a stop 20 which coöperates with a movable detent 21 slidably mounted in a guide 22 on the housing or body of the toy and having on its outer end a hand piece 23 by means 105 of which it can be moved downward into the path of a stop 20 when the motor-supporting frame is at either end of the main frame. A spring 24 holds the detent 21 normally out of the path of the stop. In the present 110 toy, however, I have provided means for imparting movement to the inertia wheel by means of a crank and to this end I have mounted in the motor-supporting frame a shaft 25 having thereon a pinion 26 connected by a suitable train of gearing 27 with the gear 14 which meshes with the inertia wheel shaft 10. Thus, by means of a crank applied to the shaft 25 rotatory movement may be imparted to the inertia wheel. The 115 stop 20 on the motor-supporting frame has a central notch 28 to receive the detent 21 and retain the motor-supporting frame in its central position during the operation of the winding mechanism.

While I have shown and described one embodiment of my invention it will be understood that this has been chosen for the purposes of illustration only and that I do not desire to be limited to the details of con- 130

struction shown and described, for obvious modifications will occur to a person skilled in the art.

Having thus fully described my invention, what I claim as new and desire to secure by Letters Patent, is:—

1. In a toy, the combination, with a main frame having two driving wheels arranged one in advance of the other, of a motor-supporting frame mounted on said main frame and having bodily movement relatively thereto, a motor carried by said motor-supporting frame, two driving pinions carried by said motor-supporting frame adapted to engage the respective driving wheels on said main frame, and means for connecting said driving pinions with said motor to cause them to rotate in opposite directions, whereby when in engagement with their respective driving wheels they will propel said toy in opposite directions.
2. In a toy, the combination, with a main frame having two driving wheels arranged one in advance of the other, of a motor-supporting frame, a motor carried thereby, two driving pinions carried by said frame, and a connection between said driving pinions and said motor to cause said pinions to rotate in opposite directions, said motor-supporting frame having free bodily movement upon said main frame to cause said driving pinions to alternately engage the respective driving wheels.
3. In a toy, the combination, with a main frame having two driving wheels arranged one in advance of the other, of a motor-supporting frame slidably mounted on said main frame, a motor mounted on said frame, two driving pinions carried by said frame, and connections between said pinions and said motor to cause the pinions to rotate in opposite directions, said pinions being arranged to alternately engage said driving wheels.
4. In a toy, the combination, with a main frame having two driving wheels arranged one in advance of the other, of a motor-supporting frame slidably mounted on said main frame, a motor mounted on said frame, two driving pinions carried by said frame, and connections between said pinions and said motor to cause the pinions to rotate in opposite directions, said pinions being held against vertical movement relatively to said motor-supporting frame and said motor-supporting frame being capable of vertical movement relatively to said driving wheels, whereby when one of said pinions is moved into engagement with its driving wheel, the weight of said motor-supporting frame will rest upon said pinion.
5. In a toy, the combination, with a main frame having two driving wheels arranged one in advance of the other, of a motor-supporting frame slidably mounted on said

main frame, an inertia wheel carried by said motor-supporting frame, driving pinions mounted on said motor-supporting frame and adapted to alternately engage said driving wheels, and gearing connecting said pinions with said inertia wheel to cause said pinions to be rotated in opposite directions by the rotation of said wheel in a single direction.

6. In a toy, the combination, with ground wheels, and a main frame carried by said wheels and capable of vertical movement relatively thereto, of a motor-supporting frame slidably mounted on said main frame and connected thereto to cause it to move vertically with said main frame, a motor carried by said motor-supporting frame, driving pinions carried by said motor-supporting frame and arranged to alternately engage the respective driving wheels, said driving pinions being so arranged that when one of them is brought into operative engagement with its wheel vertical movement will be imparted to said motor-supporting frame and said main frame to cause a portion of the weight of said frames to be supported by said pinion.

7. In a toy, the combination, with a driving wheel and a main frame mounted thereon, of a motor-supporting frame slidably mounted on said main frame and capable of vertical movement relatively thereto, a motor carried by said motor-supporting frame, a pinion carried by said motor-supporting frame, connected with said motor and so arranged when brought into operative engagement with said driving wheel to impart vertical movement to said motor-supporting frame.

8. In a toy, the combination, with a driving wheel, and a main frame mounted on said wheel and capable of vertical movement relatively thereto, of a motor-supporting frame slidably mounted on said main frame and connected thereto for vertical movement in unison therewith, a motor carried by said motor-supporting frame, a driving pinion carried by said motor-supporting frame, connected with said motor, movable into and out of operative engagement with said driving wheel by the sliding movement of said motor-supporting frame and arranged to impart vertical movement to said motor-supporting frame and said main frame when moved into operative engagement with said driving wheel.

9. In a toy, the combination, with a driving wheel and a main frame mounted thereon, of a motor-supporting frame slidably mounted on said main frame and capable of vertical movement relatively thereto, a motor carried by said motor-supporting frame, a pinion carried by said motor-supporting frame, connected with said motor and arranged when brought into operative engage-

- ment with said driving wheel to impart vertical movement to said motor-supporting frame, and means to hold said pinion in engagement with said driving wheel.
- 5 10. In a toy, the combination, with a driving wheel and a main frame mounted thereon, of a motor-supporting frame slidably mounted on said main frame and capable of vertical movement relatively thereto, an 10 inertia wheel carried by said motor-supporting frame, a pinion carried by said motor-supporting frame, connected with said inertia wheel and arranged when brought into operative engagement with said driving 15 wheel to impart vertical movement to said motor-supporting frame, and means to hold said pinion in engagement with said driving wheel, and manually operated means for rotating said inertia wheel.
- 20 11. In a toy, the combination, with a driving wheel and a main frame mounted thereon, of a motor-supporting frame slidably mounted on said main frame and capable of vertical movement relatively thereto, an 25 inertia wheel carried by said motor-supporting frame, a pinion carried by said motor-supporting frame, connected with said inertia wheel and arranged when brought into operative engagement with said driving 30 wheel to impart vertical movement to said motor-supporting frame, means to hold said pinion in engagement with said driving wheel, manually operated means for rotating said inertia wheel, and means for holding 35 said pinion out of engagement with said driving wheel while said means is being actuated.
12. In a toy, the combination, with driving wheels arranged to drive said toy in opposite directions, a main frame mounted on said driving wheels and comprising side members having longitudinal slots therein, of a motor-supporting frame having guides mounted in said slots in said main frame and 40 free to move therein, of a motor carried by said motor-supporting frame, driving pinions carried by said motor-supporting frame, connected with said motor to rotate in opposite directions and arranged to be 45 moved into engagement with the respective driving wheels and to receive a portion of the weight of said motor-supporting frame when moved into operative engagement with said respective driving wheels.
- 50 13. In a toy, the combination, with driving wheels arranged to drive said toy in opposite directions, a main frame mounted on said driving wheels and comprising side members having longitudinal slots therein, of a motor-supporting frame having guides mounted in slots in said main frame and 55 free to move therein, of a motor carried by said motor-supporting frame, driving pinions carried by said motor-supporting frame, connected with said motor to rotate in opposite directions and adapted to be 60 connected with said motor to rotate in oppo-
- site directions and arranged to be moved into engagement with the respective driving wheels and to receive a portion of the weight of said motor-supporting frame when moved into operative engagement with said respective driving wheels, manually operated means for actuating said motor, and means to hold both of said driving pinions out of engagement with their wheels while said manually actuated means is being operated.
- 65 14. In a toy, the combination, with driving wheels arranged to drive said toy in opposite directions, a main frame mounted on said driving wheels and comprising side members having longitudinal slots therein, of a motor-supporting frame having guides mounted in the slots in said main frame and free to move therein, an inertia wheel carried by said motor-supporting frame, driving pinions carried by said motor-supporting frame, connected with said inertia wheel to rotate in opposite directions and arranged to be moved into engagement with the respective driving wheels and to receive a portion of the weight of said motor-supporting frame when moved into operative engagement with said respective driving wheels, and means to hold either of said driving pinions in engagement with its driving wheel to permit movement to be imparted to said inertia wheel by moving said driving wheel over the floor.
- 70 15. In a toy, the combination, with ground wheels arranged one in front of the other, a main frame mounted on said ground wheels and capable of vertical movement relatively thereto, said main frame comprising side members having longitudinal slots therein, of a motor-supporting frame having guides extending into and freely movable in said slots, an inertia wheel carried by said motor-supporting frame, driving pinions carried by said motor-supporting frame, connections between said driving pinions and said inertia wheel to cause said driving pinions to rotate in opposite directions, said driving pinions being arranged to be alternately moved into engagement with the respective driving wheels and having their axes arranged above the plane of the upper edges of said driving wheels a distance less than the radius of said driving pinions, whereby, when one of said pinions is moved into a position with its axis substantially above the axis of its driving wheel a portion of the weight of said motor-supporting frame will be imposed upon said pinion.
- 75 16. In a toy, the combination, with a main frame, ground wheels journaled in said main frame and arranged one in advance of the other, of a motor-supporting frame mounted upon said main frame, a motor carried thereby, driving pinions journaled in said motor-supporting frame and adapted to be moved into engagement with the respective
- 80 85 90 95 100 105 110 115 120 125 130

driving wheels, said motor-supporting frame being mounted for free movement, whereby, when said toy is moving in one direction the jar occasioned by its contact with an obstruction will impart movement to said motor-supporting frame and disconnect one of said pinions from its driving wheel and connect the other of said pinions with its driving

wheel and thereby reverse the movement of said toy.

In testimony whereof, I affix my signature in presence of two witnesses.
